EXTENSION HANGER FOR A MEAT HOOK OR THE LIKE

Walter A. Reich, Kansas City, Mo., assignor to A. Reich
& Sons, Inc., Kansas City, Mo., a corporation of Missouri

Filed June 6, 1966, Ser. No. 2,579

Term of patent 7 years

(Cl. D11—1)

Fig.1.

Fig.2.

Fig.3.

Fig.4.

Fig.5.

FIG. 1 is a front elevational view of an extension hanger for a meat hook or the like, showing my new design;

FIG. 2 is a side elevational view thereof;

FIG. 3 is a rear elevational view thereof;

FIG. 4 is a top plan view thereof; and

FIG. 5 is a bottom plan view of an extension hanger for a meat hook or the like.

I claim:

The ornamental design for an extension hanger for a meat hook or the like, as shown.
